Primary Examiner — Cynthia R Underwood

(74) Attorney, Agent, or Firm — Workman Nydegger

(57) **CLAIM**

The ornamental design for a hinge cover, as shown and described.

DESCRIPTION

FIG. 1 is a perspective view of an embodiment of a hinge cover.

FIG. 2 is a top plan view according to the embodiment of FIG. 1.

FIG. 3 is a bottom plan view according to the embodiment of FIG. 1.

FIG. 4 is a front elevational view according to the embodiment of FIG. 1.

FIG. 5 is a rear elevational view according to the embodiment of FIG. 1.

FIG. 6 is a first side elevational view according to the embodiment of FIG. 1; and,

FIG. 7 is a second side elevational view according to the embodiment of FIG. 1.
